Primary Examiner — Karen Kearney*Assistant Examiner* — Katherine Holbrow(74) *Attorney, Agent, or Firm* — Abbey A. Lopez; David W. Weirich(57) **CLAIM**

The ornamental design for a display screen with icon, as shown and described.

DESCRIPTION

The FIGURE is a front view of an icon for a display screen, or product or packaging with surface ornamentation showing our new design.

The broken lines showing of the electronic device, display screen, text, and graphical user interface are included for the purpose of illustrating environmental structure and portions of the article and form no part of the claimed design.
